(57) **CLAIM**

The ornamental design for a peep hole cover, as shown and described.

DESCRIPTION

FIG. 1 is a perspective view of a peep hole cover of my invention in use, on a door shown in phantom;

FIG. 2 is a side view of a peep hole cover of my invention, in use on a door shown in phantom;

FIG. 3 is a top plan view of a peep hole cover of my invention in use;

FIG. 4 is a bottom plan view thereof, based on FIG. 1;

FIG. 5 is a front plan view thereof, based on FIG. 1;

FIG. 6 is a rear plan view thereof and a reverse view of FIG. 5;

FIG. 7 is a side view thereof, based on FIG. 1;

FIG. 8 is a side view thereof, and a reverse view of FIG. 7;

FIG. 9 is a perspective, exploded view of a peep hole cover of my invention;

FIG. 10 is a front view of an elliptical peep hole cover of my invention, the only difference being the shape;

FIG. 11 is a front view of an octagonal peep hole cover of my invention, the only difference being the shape;

FIG. 12 is a front view of an diamond peep hole cover of my invention, the only difference being the shape;

FIG. 13 is a front view of an square peep hole cover of my invention, the only difference being the shape; and,

FIG. 14 is a front view of an triangular peep hole cover of my invention, the only difference being the shape.

The broken lines form no part of the claimed design.
